UNITED STATES PATENT OFFICE.

HOWARD MASTERSON, OF BOZEMAN, MONTANA.

DESIGN FOR A TRAFFIC-SIGNAL.

51,347.

Specification for Design.

Patented Oct. 9, 1917.

Application filed July 13, 1917. Serial No. 180,453. Term of patent 14 years.

To all whom it may concern:

Be it known that I, HOWARD MASTERSON, a citizen of the United States, residing at Bozeman, in the county of Gallatin and State of Montana, have invented a new, original, and ornamental Design for Traffic-Signals, of which the following is a specification, reference being had to the accompanying drawing, forming a part thereof.

The figure is a front elevation of a traffic signal, showing my new design.

I claim:

The ornamental design for a traffic signal, as shown.

HOWARD MASTERSON.

Witnesses:

ROBT. KECK,
EMILY MASTERSON.
